UNITED STATES PATENT OFFICE

SILAS I. ATWATER, OF NEW YORK, N. Y.

CHECK-PROTECTOR.

No. 826,135.

Specification of Letters Patent.

Patented July 17, 1906.

Application filed May 31, 1904. Serial No. 210,544.

To all whom it may concern:

Be it known that I, SILAS I. ATWATER, a citizen of the United States, residing at New York, in the county and State of New York, 5 have invented certain new and useful Improvements in Check-Protectors, of which the following is a specification.

The present invention relates to improvements in check-protectors or devices by 10 means of which the alteration of bank checks or drafts may be prevented.

The device consists, essentially, of two members or sections, which are normally forced apart or held separated by a yielding 15 or spring connection and each of which is provided on its inner face with means for indenting a check placed between said jaw-like members when the latter are forced together or closed thereon.

20 It may be made in various forms and, as shown in the accompanying drawings, adapted for other uses than that for which it is primarily designed.

In the accompanying drawings, Figure 1 is 25 a plan view of one embodiment of the invention, a portion of the outer covering being removed to expose one of the indenting-plates. Fig. 2 is a side elevation of the same. Fig. 3 is a sectional view on the line 3-3 of Fig. 2.

30 Referring to the drawings, in the several figures of which like reference characters designate corresponding parts, the device will be seen to comprise two jaw-like members or sections, which are connected at one end by 35 means that act to normally hold said members apart, so that a check may be readily inserted between them.

To the inner face of each jaw is secured a 40 plate 1, provided with a serrated or roughened face, said plates acting to indent a check placed between them when the jaws are compressed or forced inwardly, as by pressure of the user's hand. Preferably the body 45 of each jaw consists of a relatively thin metal strip 2, to which the plates 1 are attached, and an outer covering-piece 3. The strips 2 are of greater length than the cover-pieces 3 and are suitably connected to hold the jaws in separated or open position and to restore 50 them to such position after they are relieved

of the pressure applied when using the device. As shown, each of said strips 2 is curved or bent, as at 4, between the point of connection of said strips and the adjacent ends of the cover-pieces 3. If desired, one of 55 said strips 2 may be of such length and form as to provide a relatively long slender blade 5, constituting a paper-cutter for which the jaw-like members of the check-protector provide a handle. Such blade may, however, 60 be omitted, and the device will then be of such size as to be readily carried in the pocket.

In using the device the portion of a check bearing the figures indicating the amount for 65 which the check is drawn is inserted between the jaws and said jaws compressed or forced inwardly to grip the check, the roughened plates 1 producing a series of indentations in the portion of the check between them, thus 70 rendering alteration of the figures appearing on that portion impossible.

Having thus described the invention, what is claimed, and desired to be secured by Letters Patent, is—

75 1. An article for the purpose described comprising two yielding plates connected together and bent or curved in opposite directions adjacent their point of connection, and supplemental plates secured to the inner faces of the first said plates and having opposing roughened surfaces.

2. An article for the purpose described comprising two metal plates connected together and each having an intermediate 85 curved section, said curved sections extending in opposite directions, supplemental plates secured to the inner faces of the first said plates and having opposing roughened surfaces, and a cover-piece 3 secured to the 90 outer face of each of the first said plates, said main plates and cover-pieces projecting beyond the supplemental plates at all points.

In testimony whereof I have signed my name to this specification in the presence of 95 two subscribing witnesses.

SILAS I. ATWATER.
